APPARATUS FOR MANUFACTURING PULP ARTICLES

Merle P. Chaplin, South Portland, Maine, assignor to Chaplin Corporation, Portland, Maine, a corporation of Maine

Original application April 30, 1942, Serial No. 441,100, now Patent No. 2,494,743, dated January 17, 1950. Divided and this application September 27, 1949, Serial No. 118,169

6 Claims. (Cl. 92—57)

This invention relates to an apparatus for manufacturing pulp articles.

In the making of certain moulded pulp articles it is desirable to not only mould them from the wood or other pulp mixtures, but also to finish one or both sides of the article with either a smooth finish, or one of some special pattern. The finishing of articles of this kind makes it also desirable to dry them by removing by heat the water or other liquid left in the article after it has been moulded from the liquid pulp mixture. It is further desirable in many instances to add a surface coating or color to the dry and finished article, or to print some special pattern or design on it.

In order to accomplish these several objects and operations it is desirable that they be done automatically by passing the article through the several operations on a single machine, as shown in the drawings which form a part of this specification.

A particular example of a moulded pulp article which requires the several operations and treatment outlined above are moulded pulp bottle caps or hoods. These articles should be smooth and attractive on the outside or top, and the top may also be printed in one or more colors.

This application is a division of application Serial Number 441,100, filed by me on April 30, 1942, upon which Patent 2,494,743 was issued on January 17, 1950.

Referring to the drawings—

Fig. 1 is a diagrammatic elevation of a machine which is made according to and embodying my invention; and

Fig. 2 is a plan view, also diagrammatic, of the machine shown in Fig. 1.

In the machine shown in the drawings the articles are moulded or formed on a plurality of dies on a cylindrical drum 1, to which a vacuum may be applied as described in my Patent No. 1,845,830, issued February 16, 1932. A transfer die 2 takes the articles from the forming dies and transfers it to the drying dies 3. These drying dies 3 then compress the article between or against the finishing dies 4, which serve to smooth the surface of the article, or to impart to it some design. Heat is applied to the drying dies 3, which are perforated, and the water of evaporation is drawn through the dies and away from the article.

The dies 3 and 4 compress the article between them for a sufficient length of time to completely dry the water from the article, and if necessary or desirable, the finishing die 4 may also be heated. After the articles have been dried, they are removed from the drying dies by a transfer die similar in operation to that used to transfer the article from the forming die to the drying die.

The articles are then held on the printing holding dies 5, which move under printing or coating dies 6. As many printing or coating positions as are necessary can be provided. After being printed or coated or both, the articles are removed from the printing holding dies 5

2

by a transfer die similar in operation to that used either to transfer the article from 1 to 3 or from 3 to 5.

It will be observed that the motions of the several dies are step by step, each set of dies being at rest when an article is being transferred to it or from it. It will also be observed that the transfer dies have two motions, one a reciprocating motion between the two dies and the other an up-and-down motion something greater than the depth of the article so that the article is drawn directly away from the die during the transfer operation.

The smoothing or finishing dies revolve about a vertical shaft and are fixed thereto. The drying dies have a vertical reciprocating movement to provide for delivering the articles to the smoothing dies, and an upward movement to compress the articles between the drying and smoothing dies.

If desirable, more than one deposit of pulp or other material can be made on the forming dies 1. This can be done either by providing two or more pulp tanks 7 or 20 by adding a coating on the article while it is on the forming die, and during its travel from the pulp tank 7 to the position of transfer. The article on the transfer die can also be smoothed on its exposed surface at, say, the horizontal position of the die, or halfway between its 25 travel from forming to transfer.

Suitable mechanism is provided for driving the various parts of the machine in desired synchronism. These mechanisms are not shown, as they are well known in the art. For example, the movement of the drying dies 3 into and out of compressing relation with respect to the smoothing or finishing dies 4, as they collectively rotate about the vertical shaft which supports the latter dies, may be accomplished or controlled by the fixed cam track shown in section below the operating stems of said dies in Fig. 1 of the drawing. United States Patent No. 1,377,342, issued May 10, 1921, to H. P. Harbrecht, discloses similar mechanism. That patent shows, in Fig. 2, a fixed cam 16 having therein a groove or cam track 16a in which ride the cam followers 40 connected to the stems of the several molds 44 and bodily rotation of these molds about the central shaft 13 causes the molds to be vertically raised and lowered in succession.

Step-by-step rotation of the smoothing and drying dies about their central shaft may be accomplished by rotating this shaft by Geneva gearing, as shown in United States Patent No. 827,765, issued August 7, 1906, to G. R. Ward, which illustrates a well-known construction for this purpose. In that patent the star wheel 7 affixed to the central shaft is periodically rotated by a roller 5 on the constantly rotating wheel 6 for the same purpose.

The transfer dies may be periodically vertically and laterally shifted, as herein described, by such transfer mechanism as that exemplified by United States Patent No. 1,248,381, issued November 27, 1917, to F. E. Neubert. In this patent precipitated layers of pulp, formed on the molds 2, are couched in the die casings, and are then moved laterally with the carrier 16 of that patent to transfer the formed pulp articles to another part of the machine and then lower them. This patent thus discloses suitable mechanism old in the art for raising and lowering the formed articles vertically and transferring them laterally.

Many other novel and useful operations may be performed, and the article may receive other treatments while passing through the machine as it may be automatically transferred as many times as may be necessary by the same device already described. Other novel features may be made within the spirit and scope of this invention and I intend no limitations other than those set forth in the appended claims.

I claim:

1. A pulp-molding machine comprising a pulp tank, a horizontal shaft above the tank, a rotatable carrier mounted on the shaft, a forming die on the carrier and moved by said carrier in a vertical path through the tank to a horizontal position above the tank, a vertical shaft laterally spaced from the carrier, a horizontal drying die supported on the vertical shaft for movement around the axis of said vertical shaft in a circular path laterally spaced from the path of movement of the forming die, a permanently horizontal transfer die movable vertically toward and away from the forming die and the drying die and laterally across the space between the paths of movement of the forming die and the drying die.

2. A pulp-molding machine comprising a pulp tank, a horizontal shaft above the tank, a rotatable carrier mounted on said shaft, a forming die on the carrier and moved by said carrier in a vertical path through the tank to a horizontal position above the tank, a vertical shaft laterally spaced from the carrier, a pair of horizontal drying dies supported in permanent vertical alinement on the vertical shaft for movement around the axis of said vertical shaft in circular paths laterally spaced from the path of movement of the forming die, a permanently horizontal transfer die movable vertically toward and away from the forming die and the drying dies and laterally across the space between the path of movement of the forming die and the paths of movement of the drying dies from a position in vertical alinement with the forming die to a position between and in vertical alinement with the drying dies.

3. A pulp-molding machine comprising a pulp tank, a horizontal shaft above the tank, a rotatable carrier mounted on said shaft, a forming die on the carrier and moved by said carrier in a vertical path through the tank to a horizontal position above the tank, a vertical shaft laterally spaced from the carrier, a pair of horizontal drying dies supported in permanent vertical alinement on the vertical shaft for movement around the axis of said vertical shaft in circular paths laterally spaced from the path of movement of the forming die, mechanism for moving one of said drying dies vertically toward and away from the other as said drying dies move along their circular paths, a permanently horizontal transfer die movable vertically toward and away from the forming die and between the drying dies and laterally across the space between the path of movement of the forming die and the paths of movement of the drying dies from a position in vertical alinement with the forming die to a position between and in vertical alinement with said drying dies.

4. A pulp-molding machine comprising a pulp tank, a horizontal shaft above the tank, a rotatable carrier mounted on the shaft, a plurality of angularly spaced forming dies on the carrier moved successively by the carrier in a vertical path through the tank to a horizontal position above the tank, a vertical shaft laterally spaced from the carrier, a plurality of pairs of horizontal drying dies supported on the vertical shaft for movement around the axis

of said vertical shaft in circular paths laterally spaced from the path of movement of the forming dies, the drying dies of each pair being in permanent vertical alinement, mechanism for moving one of the drying dies of each pair vertically toward and away from the other drying die of said pair as said drying dies move along their circular paths, a permanently horizontal transfer die movable vertically toward and away from the forming dies and between the drying dies and laterally across the space between the paths of movement of the forming dies and the drying dies from a position in vertical alinement with one of the forming dies to a position between and in vertical alinement with a pair of drying dies.

5. A pulp molding machine comprising: a pulp tank, a forming unit embodying a forming die and mounted on horizontal bearings whereby the forming die is movable in a vertical path through the tank to a horizontal position above the tank, a drying unit spaced laterally from the forming unit and having bearings to mount it for rotation and including a drying die mounted off center of said unit whereby said drying die is movable with said unit in a circular horizontal path about the axis of said unit, a transfer unit including a permanently horizontal transfer die, and means to move said transfer die from a position of coaxial alinement with a forming die to a position of coaxial alinement with a drying die and vice versa across the lateral space between said latter dies and to move said transfer die vertically into and out of cooperation with the forming and drying dies when respectively in alined relation with each of them.

6. A pulp molding machine comprising: a pulp tank, a horizontal shaft, a rotatable die carrier on said shaft, a forming die supported on the carrier and rotatable therewith from a lower position in the pulp tank to an inverted position above the tank, a receiving die spaced laterally from said carrier and mounted for movement about an axis, a transfer die, and means to move the transfer die with the article thereon from a position of engagement with the inverted article on the forming die laterally across the space between the forming die and the receiving die, while maintaining the article in such inverted position.
